LOUIS C. MILLER, OF VERONA BOROUGH, NEW JERSEY.

FIRE-ALARM SYSTEM AND CONTROLLING MEANS THEREFOR.

Application filed May 5, 1921. Serial No. 466,941.

To all whom it may concern:

Be it known that I, LOUIS C. MILLER, a citizen of the United States, residing in the borough of Verona, county of Essex, and 5 State of New Jersey, have invented a new and useful Improvement in Fire-Alarm Systems and Controlling Means Therefor, of which the following is a description.

This invention has reference to fire alarm 10 systems and particularly relates to controlling means for said systems, such that, upon a rise of temperature, a thermostatic device will operate so as to transmit a signal, or set in action an alarm, indicator, or other 15 means by which to give notice of the existence of a fire.

Among the objects of my invention may be noted the following: to provide a system 20 of means by which an alarm may be sounded, or a signal given, in case of fire or undue rise in temperature in any predetermined place, the control being by medium of one or more devices capable of being operated in the presence of a low degree of heat; to provide 25 a system as just stated adapted to be set in operation by a controlling device actuated by the fusing of a metal at a low degree of heat; to provide a system of means wherein the vitalizing element is a key, connector or 30 controller, or a plurality of the same, inserted in a signal line, the said controller comprising a compound body which is held in a locked, or normal position, by solder 35 capable of fusing at a low degree of heat, and the movement of which body causes a circuit, line, conduit or other medium to give way or be released, so that an alarm is set in action or a signal is operated; to provide an 40 alarm or signaling system comprising one or more controllers which may be set in action by a low degree of heat, and which, at the completion of its action, is locked in such position that it can be further utilized in the system by a reversal of position; to provide 45 a signaling or fire alarm system with a plurality of diversified branches communicating with a single alarm or signaling device conveniently located, or a central or predetermined station, and wherein the control of 50 the diversified branches is brought about by a connector, controller or device which is permitted to go into action in the presence of a low degree of heat by reason of the fus-

ing of a component part thereof; to provide a fire alarm system comprising diversified 55 leads, a junction-box or apparatus, and an alarm or signaling device, wherein the controlling means is a device which may be set in action by the fusing of a metal in the presence of a low degree of heat, and which 60 controlling device is automatically reset for further or continued service as the result of its functional operation; and to provide certain details of construction and certain arrangements of lines, leads, or branches 65 constituting a system of means for setting in action an alarm or signal, which are simple, compact, economical to construct and maintain, and which are strong, durable and effective. 70

With the above objects in view and others which will be set forth during the course of this description, my invention consists in the parts, features, elements and combinations thereof hereinafter described and 75 claimed.

In order that my invention may be clearly understood, I have provided drawings wherein:

Figure 1 is a view showing, partly in elevation and section, certain details constituting a single line system and control embodying my invention, the view being broken in several places to convey the idea of indefinite length; 80

Figure 2 is a view, partly in elevation and section, of a terminal and alarm of a multiplex system of signaling embodying my invention;

Figure 3 is a top plan view of the terminal 90 of Figure 2;

Figure 4 is a view showing in end elevation one of the bridges of Figure 1, the view being somewhat enlarged;

Figure 5 is a plan view showing a signaling system embodying diversified leads and a junction-box embodying my invention; 95

Figure 6 is a diagrammatic view showing a signaling system embodying my invention 100 wherein a plurality of diversified leads and junction-boxes are employed.

Referring to the drawings, and particularly to Figure 1, which shows a single line system, a plurality of bridges or brackets 105 are provided for attachment to the ceiling,

walls, or any supporting medium established for the installation of the system, each of said bridges consisting of a body portion 1, adapted to be secured in place in any suitable manner, having at each end a looped, supporting member 2, arranged at an angle to the body portion, the end of the looped portion being held by a screw 3 on which is turned a nut 4, the loop 2 thus forming a clamp which adjustably holds a conduit section 5 in the form of a pipe or suitably formed tube through which wires 6 may freely pass and which wires are protected by the conduits from moisture, atmospheric conditions, dust, or other accumulations, the tendency of which might be to impair the efficiency of the wires or affect their operation. The bridges are adapted to be applied to any surface and the form of the body portion 1 is not material, the essential being that it shall be of such form as to afford a means of support and attachment to anything and in any place the installation of the system is to be made. Also the bridge may be more or less extensive so as to locate the loops 2 as far apart as may be required to enable the controlling devices to be inserted and suspended, as presently described. Between the loops 2 of the bridges, the conduits 5 are omitted, and in the space between the loops the adjacent ends of the leads or wires 6 are connected to a controlling device, in this instance of my invention consisting of a compound member or key similar to that disclosed in my Patent #1,112,226, granted Sept. 29, 1914. The controlling device consists of two disks, one of which 7 is shown in Figure 1, pivoted together centrally at 8, and between the two having a circular pocket 9, formed by registering grooves in the respective disks and preferably sinuous in outline, and adapted to contain a solder or metal fusible at a low degree of heat. The metal when set holds the disks 7 securely together so that the same cannot be shifted relatively even when subjected to considerable tension or strain. One of the disks 7 is provided with two arms 10, 13 extending approximately radially therefrom on opposite sides of the disk, the arms being bent slightly inwardly relatively to the inner surface of the disk. The other disk is provided with arms 11, 12 arranged in the same manner and bent slightly inwardly toward the inner surface of the disk, this arrangement of the arms of the respective disks causing adjacent arms at their bases 14 to engage each other when the disks rotate on their pivot. The adjacent cooperative arms thus operate as stops forming a limitation to the rotation of the disks. The inner edge of each of the arms of the several disks is cut away longitudinally as at 15 and is provided with one or more notches 16 adapted to receive the loops at the ends

of the wires or leads 6 by which the controlling device or key is suspended in position between the loops 2 of the bridges, one controlling device to each bridge, if desired, throughout the system. The shoulders 14 prevent the notched portions of the arms of the disks from engaging each other, thus avoiding interference with the loops of the wires or leads connected to said arms; and the shoulders 14 of one pair of arms constitute stops for the opposite arms and limit the movement of the controlling device or key, when set in operation, to prevent the said arms from coming together and being set so that the wire loops cannot be engaged with the notches thereof when the key is reversed and reset for further operation in resetting and priming the signaling line.

At one terminal of the line, which I will call the "tension terminal," a tube 17 is clamped in the terminal loop 18 of the terminal bridge, said tube having a shoulder 19 to prevent displacement. A screw-threaded bar 20 slides freely in the tube 17 and its inner end is connected to a key or controller, as by having an eye in which is looped the end of a terminal wire of the system, the screw-threaded outer end of the bar 20 having a jam-nut 21 abutting against the shoulder 19 of the tube 17, so as to draw the entire signal line taut, or to draw it up sufficiently to take out all slack or sag which will naturally occur when the controlling keys are being set in place. At the opposite terminal of the line, or the one nearest the alarm or signaling device, which, for convenience will be termed the "tripping terminal," the bridge or bracket will have a trip-bar 22 loose in its terminal loop 23, the inner end of which bar is provided with an eye in which is looped the end of a terminal wire of the system, and said bar 22 is provided with a collar 24 against which one end of a coiled expansion spring 25 engages, the opposite end of which engages the bridge loop 23, the spring surrounding the bar. The outer end of the bar 22 is extended into the signaling device 26 and operates in any approved manner to trip the same and set it in action, in the event the line breaks or gives way by reason of the operation of any one of the controlling devices or keys. In this instance of my invention, I have shown an alarm, gong or bell provided with any approved form of motor, escapement, and hammer adapted to be tripped into action to cause the gong to be rung. According to my invention, the form of the alarm or signaling device is not important, nor the manner in which the same is tripped into action; but, as showing a means for the purpose, the bar 22 has a cam 27 thereon, in the form of a truncated cone, which engages the hammer arm 28, so that, when the alarm is set, the hammer arm 130

will engage the cam at its greatest diameter and will be prevented from operating under the influence of the escapement to ring the gong. When the trip-bar 22 is shifted to allow the hammer arm 28 to ring the gong, said arm will operate opposite the smallest diameter of the cam 27, at which point there will be ample clearance for complete freedom of action of said arm. The setting of the hammer arm 28 out of operation will be brought about by shifting the trip-bar 22 under the influence of the line wires and connecting keys when the tension device at the tension terminal of the line is adjusted to take up the slack. This operation also puts the spring 25 under compression, so that the normal tendency of the latter is to press the trip-bar toward the alarm to shift the cam 27 and release the hammer arm. The holding of the hammer arm by the cam on the trip-bar locks the escapement, so that the motor of the gong cannot operate. When, however, anything gives way in the line, for any cause or reason, the spring 25 will quickly shift the trip-bar which will shift the cam out of control of the hammer arm, thus releasing the latter and the escapement, so that the motor of the gong will be set in operation and the hammer arm will be actuated to ring the gong. This will be true of any form of signaling device at 26, the latter being tripped into action automatically and set for action simultaneously with the adjustment of the tension on the signal line. When thus set for action, the cam 27 will be drawn with its small-end 29 against the base 30 of the device 26, so that the cam 27, at its large end, cannot be drawn out of place or out of cooperative position relatively to the hammer arm 28. Likewise, when the trip-bar 22 is shifted by the spring 25, its movement will be limited by the collar 31 thereon engaging the loop 23 of the bracket, thus insuring that the hammer arm will not be interfered with and that it will be always in position to operate freely to ring the gong.

In Figures 2 and 3, I have shown a form of my invention wherein a plurality of signaling lines, composed of the elements shown in Figure 1, are brought to a tripping terminal bridge 32 which has a bearing member 33 provided with a plurality of apertures through which pass bar terminals 34, each of which is connected at one end to a line wire 6, which is looped in an eye 35 thereof. Each of the bars 34 also passes through a bearing member 36 carried by the bridge 32. An expansion spring 37 surrounds each bar 34 and has one end engaged with the member 33 and the opposite end engaged with a collar 38 fixed on said terminal bar, the normal tendency of the spring being to force the bar outwardly so that the bar will be automatically shifted when the line gives way. A swinging tripping wing 39 is arranged adjacent the end of the terminal bars and in position to be engaged by any one of said bars and shifted so as to engage the trip-bar 40 of an alarm or signal 70 26 which, in this instance of my invention, will have at its inner end within the gong or alarm device a surrounding expansion spring 41, the normal tendency of which will be to force the trip-bar toward the wing 39 75 so that the latter, when acted upon by one or more of the terminal bars, will in turn operate upon the end of the trip-bar and force the same inwardly so as to compress the spring 41 surrounding its inner end and 80 shift the cam 27 so as to release the escapement. The motor of the gong will then operate the hammer arm to sound the alarm. The tripping wing 39 is pivoted to the ears 42 of the bridge 32, and the tripping bar 40 85 passes through the bearing 43 of said bridge. The stop collar 44 is placed on bar 40 so as to cooperate with the base 30 of the signal device. The cam 27 is the same and cooperates in the same manner with the hammer arm 28 as in Figure 1. The spring 41 bears at one end against a fixture 45 and at the other end against the cam 27. It will now be seen that, regardless of which one of the lines gives way, the wing 39 will be actuated 90 by a bar 34 to actuate the trip-bar 40 and set the alarm 26 in operation. This form of my invention compasses the idea of means of a plurality of signal lines being brought to a common terminal adjacent the alarm and 100 arranged compactly so that any one of the lines in giving way can operate the signal or alarm device. When the tension terminals of the lines are all set, the wing 39 will swing into the position of Figure 2 105 under the influence of the trip-bar 40 which is automatically shifted by the spring 41 so as to cause the cam 27 to hold the hammer arm 28 out of action.

In the form of my invention shown in Figure 5, I have provided for a system of diversified branches, including a junction-box 46 in which a device is located consisting of a plurality of arms 47 pivoted together so as to produce a four-sided junction device. A coiled contractile spring 48 is connected to the two opposite pivotal points 49 of the junction device, the normal tendency of which is to draw said two pivotal points together and force the two opposite 110 pivotal points 50, 50^a apart. The junction-box is provided with four tubular outlets 51 through which the line wires 6 extend, the tubular outlets being sufficiently great in diameter to allow of considerable lateral 115 play or movement of the line wires therein. Preferably, the outlets are flared, as at 52, so as to avoid friction against the wires when the lines give way. Each of the line wires at the junction-box is connected to one 120

125 130 135 140 145 150 155 160 165 170 175 180

of the pivotal points of the junction device within the box and, when the various lines are put under tension, as heretofore described, the junction device will be held in approximately the square shape or condition shown in Figure 5, thus distending the spring 48, which latter places the junction device under tension. With the several signal lines properly set and under tension as described, the junction device within the junction-box is practically suspended, or it may be said to float within the junction-box, since it is universally movable therein and is susceptible of shifting one way or the other as tension is applied to the diversified lines, and is likewise capable of shifting therein according to which one of the diversified lines gives way by reason of the operation of a controlling device in any one of the said diversified lines. As shown in Figure 5, one of the leads will extend to the signaling device 26, the one so shown being connected to the pivotal point 50°. In the operation of this diversified system, if any one of the controlling devices or keys in one of the leads *a* or *b* gives way, the spring 48 will contract and thus shift the pivotal point 50°, thus releasing the line wire leading to the alarm, which, as described with reference to Figure 1, will shift the trip-bar 22, thus releasing the hammer arm 28 of the alarm, so that the escapement may be operated by the motor of the gong. On the other hand, if the lead *c* gives way, the junction device will be shifted bodily in the direction of the lead line running directly to the alarm, and the latter will be operated as described. If the direct alarm line *d* gives way, the alarm will be operated as previously described.

In the diagram of Figure 6, a further diversified form of signaling system is shown comprising a plurality of junction-boxes 46, junction devices 47 and leads running thereto, the junction devices in the several boxes being connected in the system so that, regardless of which one of the lines gives way, a signaling device will be operated. In this diagram all the similar parts and elements of the other forms of my invention are indicated by like characters. This system of means is adapted for very large installations and is illustrated to demonstrate the flexibility of my signaling system and its adaptability to practically every condition which may be encountered in large factories, office buildings, etc. The various leads run to junction-boxes which may be located in different parts of a large room or may be located, respectively, in a number of rooms. Each of the lines is provided with a tension device 20-21 which puts that particular line with its keys, and extending to a junction-box, under proper tension. As shown, beginning at the right hand side of Figure 6, the lead at the left

side of the junction-box, as well as the one at the right side thereof, extends to a similar junction-box, which latter is connected in similar manner to another junction-box, which in turn is connected to another junction-box, from the left hand side of which extends the terminal line having the alarm 26 at the terminal end thereof. Leads may extend from the several junction-boxes in the several directions shown; but, in some instances, it may be found necessary to omit one of the leads, in which instance one side of the junction device will be anchored as at 53 in the two central units of Figure 6. The side which is anchored will have one end of the spring 48 connected therewith, so that, when a line *b* gives way, as in Figure 5, the spring will contract, thus shifting the pivotal point 50°, so as to slacken the line at that side and cause the signal to be set in operation. From this diagrammatic view illustrating the flexibility of my system, it will be seen that any number of leads can be combined, all with a view to operating a single signal at a conspicuous or advantageous point; for, if any one of the lines gives way for any reason whatsoever, the effect thereof is transmitted to the adjacent junction-box, the junction device wherein immediately transmits the signal throughout the series intervening between it and the signal device. Tension is applied in this diversified system at the end of each of the signal lines so as to draw the latter taut and maintain it thus, and, when the main line extending from the signal device is put under tension, all the junction devices in the several junction-boxes will be affected and properly set, it remaining then to set the various branch lines by manipulating the tension terminal, thus putting the entire system in order. Regardless of the cause of the break or giving way of any one of the signal lines, the signaling device will be operated and immediate investigation will take place to determine whether the cause be a fire or some defect in one or more of the lines. Thus the system can always be maintained in proper working condition, fires can be instantly detected, and can be prevented from gaining headway. In most instances it will be possible to extinguish the same by chemical devices, which will always be at hand, thus avoiding extensive damage.

Having thus described my invention, what I claim and desire to secure by Letters Patent is:

1. A system of means for signaling comprising a sectional line; a controlling device inserted between the sections; a rigid, adjustable tension terminal at one end of the line; a tripping terminal at the opposite end of the line; and an alarm operatively connected to and restrained by the tripping

- terminal; the controlling device comprising means adapted to be operated in the presence of a low degree of heat, whereby to release the tripping device to set the alarm 5 in operation.
2. A system of means for signaling comprising a sectional line; a reversible controlling device inserted between the sections; a rigid, adjustable tension terminal at one end of the line; a tripping terminal at the opposite end of the line; and an alarm operatively connected to and restrained by the tripping terminal; the controlling device comprising means adapted to be operated in the presence of a low degree of heat whereby to set the alarm in operation, and whereby to reset the controlling device for subsequent use.
3. A signaling system comprising an alarm device; a plurality of sectional line wires of indefinite length each having a terminal bar under tension; controlling devices connecting the sections of said line wires and adapted to be operated in the presence of a low degree of heat; a tripping device coupled with said alarm device and common to all said terminal bars, and adapted to be operated by any one of said bars when its line wire gives way.
4. A signaling system comprising an alarm, a tripping device therefor, a signal line extending to the tripping device, a controlling device interposed in the signal line adapted to be operated in the presence of a low degree of heat, an adjustable tension device applied to one terminal of the signal line, and a power device interposed between the tripping device and the signal line adapted to operate the tripping device when the controlling device operates.
5. A signaling system comprising a plurality of independent signal lines each having a tension terminal; a junction device for said lines; a signaling device common to all said lines; a tripping means common to all said lines and cooperating with said signaling device and with said junction device; each line having a controlling means adapted to operate in the presence of heat and thereby set in operation the tripping means without disturbing the operative condition of the other lines.
6. A signaling system comprising a plurality of independent signal lines; a junction device connecting all said lines including means for holding them under tension; a signaling device common to all said lines; a tripping means arranged cooperatively with said signaling device and said junction device, whereby when a line gives way the tripping means will actuate the signaling device without disturbing the operative condition of the other lines.
7. A signaling system comprising a plurality of diversified lines; a junction box 65 into which all said lines are extended; means within said box for connecting and holding said lines under tension; a signaling device common to all said lines; a tripping device coupled to said signaling device and to all said lines; and means in each line adapted to give way in the presence of heat so that the tripping device will operate 70 the signaling device.
8. A signaling system comprising a plurality of diversified lines; a junction box into which all said lines are extended; a floating connection within said junction box for all said lines; a signaling device, common to all said lines; a tripping device coupled to said signaling device and to all said lines; and means in each line adapted to give way in the presence of heat so that the tripping device will operate the signaling device.
9. A signaling system comprising a plurality of diversified lines; a junction box into which all said lines are extended; means within said box for connecting and holding said lines; each of the lines having an adjustable terminal; a signaling device common to all said lines; a tripping device coupled to said signaling device and to all of said lines; and means in each line adapted to give way in the presence of heat so that the tripping device will operate the signaling device.
10. A controlling key for signaling devices comprising a pair of disks pivoted together for circular movement, each of said disks having a pair of oppositely extending arms, a fusible means for holding the disks against movement, each of said arms being provided with a shoulder and a notch, the shoulders being so arranged as to interact with an adjacent arm and prevent the latter from coming together at the point where the notches are located.
11. A reversible controlling key for signaling devices, comprising a pair of pivotally connected plates adapted to move relatively; fusible means between said plates for holding them from movement; each of said plates having a pair of oppositely extending arms, and each of said arms being provided with means for limiting its movement and with means for holding a signal wire, the arms being so related that when two thereof are together in cooperative relation the other two are spread apart.
12. A system of means for signaling comprising a sectional line; a controlling device inserted between the sections; means at one end of the line for rigidly holding the same; a tripping terminal at the opposite end of the line; and an alarm operatively connected to and restrained by the tripping terminal; the controlling device comprising means adapt-

ed to be operated in the presence of a low degree of heat, whereby to release the tripping device to set the alarm in operation.

13. A signaling system comprising an alarm device; a sectional line wire of indefinite length having a terminal bar under tension and its opposite end rigidly held; controlling devices connecting the sections of

said line wire and adapted to be operated in the presence of a low degree of heat; a tripping device coupled with said alarm device and said terminal bar, and adapted to be operated by said bar when the line wire gives way. 10

LOUIS C. MILLER.
